United States Patent Office

Des. 180,800
Patented Aug. 13, 1957

180,800

MIRROR

Harry H. Mook, Memphis, Tenn., assignor to Binswanger
Mirror Company, Memphis, Tenn., a corporation of Tennessee

Application July 12, 1956, Serial No. 42,227

Term of patent 14 years

(Cl. D33—9)

FIG. 1.

FIG. 2

FIG. 3

FIG. 4

FIG. 5

Figure 1 is a plan view of a mirror embodying the design of the present invention;

Figure 2 is a partial bottom plan view of the mirror;

Figure 3 is an edge view;

Figure 4 is a vertical transverse section taken on the line 4—4 of Figure 3, and;

Figure 5 is a vertical transverse section taken on the line 5—5 of Figure 3.

I claim:

The ornamental design for a mirror, substantially as shown.

References Cited in the file of this patent

UNITED STATES PATENTS

D. 148,611 Friedman _____ Feb. 10, 1948
 D. 173,471 Bloch _____ Nov. 16, 1954

OTHER REFERENCES

Home Furnishings, March 1952, page 92, mirror bottom right, No. 1299.

Home Furnishings, September 1953, page 16, mirror bottom left, No. 1307.